DESIGN FOR AN AIRPLANE

Robert W. Ayer, Wayne, Mich., assignor to Manning & Co., Chicago, Ill., a corporation of Illinois

Application October 27, 1933. Serial No. 49,576

Term of patent 7 years

To all whom it may concern:

Be it known that I, ROBERT W. AYER, a citizen of the United States and a resident of Wayne, county of Wayne and State of Michigan, have invented a new, original, and ornamental Design for an Airplane, of which the following is a specification, reference being had to the accompanying drawings, forming a part thereof, and wherein:

Fig. 1 is a top perspective view of an airplane embodying my new design.

Fig. 2 is a view in side elevation of the same.

Fig. 3 is a top plan view of the airplane.

Fig. 4 is a view in front elevation thereof.

I claim:

The ornamental design for an airplane substantially as shown.

ROBERT W. AYER.
